UNITED STATES PATENT OFFICE.

ALLAN E. McCABE, OF RICHMOND, VIRGINIA.

WATER-HEATER FOR OIL-STOVES.

1,310,709.

Specification of Letters Patent. Patented July 22, 1919.

Application filed May 5, 1917, Serial No. 166,700. Renewed May 3, 1919. Serial No. 294,566.

To all whom it may concern:

Be it known that I, ALLAN E. McCABE, a citizen of the United States, and a resident of Richmond, in the county of Henrico and State of Virginia, have invented an Improvement in Water-Heaters for Oil-Stoves, of which the following is a specification.

My present invention relates generally to oil stoves, and more particularly to water heating attachments therefor, my object being the provision of a simple improved water heating casing constructed in such manner as to obtain maximum and effective results in its water heating operation, and capable 10 of substitution for the usual burner casing removably disposed, as at present, upon the burners of stoves of this character.

The further objects of my invention, residing for the most part in the details of construction of the substitute casing, will be apparent from the following description, detailing such construction and the advantages thereof, in which reference is made to the accompanying drawings, forming 25 part of this specification, wherein—

Figure 1 is a front elevation of a conventional oil stove in connection with which my improvements are mounted.

Fig. 2 is a detail vertical section substantially on the line 2—2 of Fig. 1.

Fig. 3 is a vertical longitudinal section through certain portions of my improvements.

Referring now to these figures, I have shown in Fig. 1, a conventional type of oil stove, generally indicated at 10, the usual burner casings 11 of which, seen at the right in Fig. 1, are, as well known, detachably mounted upon the respective burners 12, and 40 of the upright tubular form shown.

In connection with stoves of this type my invention provides a water holding heating casing 13, shown at the left in Fig. 1, and in detail in Fig. 2, which may be inserted in position to rest upon the respective burner 14 of the stove when the usual casing 11 is removed, the water casing 13 having a lower or base piece 15 in the form of an inverted frustum of a cone for direct engagement with the burner 14 and provided at its upper edge with an annular rim 16 crimped, as shown, around the contiguous flanged lower ends 17 of the inner and

outer walls 18 and 19, the latter of which, as seen particularly in Fig. 2, is tubular and of 55 the same diameter throughout.

The inner wall 18 tapers in its length and in an upward direction so as to form a water chamber 20 of annular form between the same and the outer wall 19, which gradually enlarges in cross sectional area toward the top of the casing, the particular shape of the inner wall being for the purpose of detarding or partially confining the products of combustion passing upwardly from the burner 14 so as to provide for effective heating of the water within the chamber 20, the upper extremity of the inner tapering wall 18 being crimped, as seen at 21, around the inner flanged edge of a top plate 22, the 70 outer edge of which top plate has a similar rim 23 crimped around the upper flanged edge of the outer wall 19. The inner and outer walls 18 and 19 of the improved water casing provided with my invention also have 75 lower aligned openings in which is secured a short horizontally disposed flue 24 having a door 24^a at its outer end and providing for access to the upper portion of the burner 14 extending vertically within the base 15 of 80 the casing and the lower portion of the inner wall 18.

The water casing 13 so formed, of which one may be applied to any one or more of the stove burners, is supplied from a water 85 tank 25 having an upper opening 26, as best seen in Fig. 3, provided with a hinged perforated door 27, the perforations of which provide for the outlet of steam. The tank 25, as seen in the figure last-mentioned, 90 may also have a water gage, and may be supplied with water through suitable connections with the ordinary house water supply system.

The tank 25 is connected to the water 95 casing 13 by a single feed pipe 31 extending from the base of the tank, as seen in Figs. 1 and 3, and connected at its opposite end by a threaded clamping ring 32 to a threaded nipple 33 extending laterally from 100 the outer wall 19 of the water casing in each instance, it being noted that for the best results the cross sectional area of the nipple 33 and the pipe 31 is substantially the same as that of the water space at one side of the 105 casing opposite the nipple, the pipe 31 tak-

ing care of both the inflow of water to the water casing 13 and the outflow of hot water to the tank 25.

In Fig. 1, where the water casing 13 of 5 my invention is shown as applied to one only of the series of burners of the stove, at one end of the series, the water tank 25 is shown as supported by a bracket 34 to one side of the stove.

10 Thus my invention, in addition to its effectiveness and efficiency for the purpose described in connection with the heating of water, possesses the further advantage of ready adaptability to the oil stoves of standard or conventional construction now in use, and may be applied thereto by the mere mounting of the water tank and its connections, and the substitution of one or more of the water casings 13 for one or more of 15 the usual tubular single wall casings 11.

It is to be appreciated further, that by the provision of a water space formed between the double walls of the water casing and by the tapering construction of the 20 inner wall thereof, the partially confined or retarded products of combustion from the

respective burners are prevented from wasteful dissipation and the heat of the ordinarily wasted products taken up by the water instead.

30 The tank 25 may have a draw off cock 40, one of which is seen in Fig. 1, whereby hot water may be withdrawn from the tank, as needed for use.

35 I claim:

A water heating burner casing for oil stoves having a lower base piece adapted to rest on the burner of an oil stove and provided with an upper rim forming an inwardly presented annular groove, inner and outer walls provided with lower adjacent edges having abutting flanges projecting outwardly into said groove and clasped within the rim of the said base piece, the inner wall tapering to form a water space between the 40 same and the outer wall, said space gradually increasing in width in an upward direction, and a top piece connecting the upper spaced ends of the inner and outer walls and closing the upper end of the water 45 space, for the purpose described.

ALLAN E. McCABE.
